MIXED DRINK FAUCET

Carl J. Braun, Wooster, Ohio, assignor to The Wooster Brass Company, Wooster, Ohio, a corporation of Ohio

Application May 12, 1948, Serial No. 26,499

7 Claims. (Cl. 277—4)

1

The invention relates generally to faucets for dispensing carbonated beverages, and more particularly to a novel mixed drink faucet for dispensing selectively carbonated water separately or simultaneously with a flavoring syrup or with one of several flavoring syrups.

A conventional type of faucet for carbonated beverages dispenses carbonated water and flavoring syrup separately from the dispensing spout for being mixed in a glass. This type of faucet is shown in U. S. Patent No. 2,401,914, issued June 11, 1946 to Carmelo V. DiPietro, and embodies a rotatable shutter valve having overlapping U-shaped passageways for connecting the inlet and outlet ports for the carbonated water and syrup for dispensing the carbonated water and syrup simultaneously.

With this type of prior faucet, difficulties have been experienced in maintaining a leak-proof seal between the abutting surfaces of the rotating shutter valve and the faucet body. These difficulties have been largely due to the substantial area of the abutting surfaces and to the sticky nature of the syrup which causes a residue tending to build up around the ports leading to the various passageways.

Another objection to this type of prior faucet is that it has little, if any, room in the shutter valve to provide additional ports for conducting additional kinds of syrup, because substantial space must be provided between ports in order to insure a good seal around each port.

Moreover, in all prior faucets of this type of which I have knowledge, some sort of diffusing means is required for reducing the velocity and pressure of the carbonated water so that when it is discharged into a glass, there will not be excessive agitation and turbulency resulting in the liberation of too much carbon dioxide gas, which detracts from the palatability of the drink.

It is an object of the present invention to provide a novel and improved faucet which is adapted to dispense either carbonated water alone or simultaneously with a flavoring syrup.

Another object is to provide a novel faucet which overcomes the foregoing disadvantages of prior faucets.

Another and more specific object is to provide a novel faucet which maintains a positive leak-proof seal in shut-off position for the carbonated water and syrup dispensed by the faucet.

A further object is to provide a novel faucet construction which readily accommodates additional passageways for conducting and dispensing several kinds of syrups.

2

A still further object is to provide a novel faucet which is adapted substantially to reduce the velocity and pressure of the carbonated water flowing therethrough without requiring the usual special diffusing means.

These and other objects are accomplished by the parts, constructions, arrangements, and combinations which comprise the present invention, the nature of which is set forth in the following general statement, and a preferred embodiment of which is set forth in the following description and illustrated in the accompanying drawings, and which is particularly and distinctly pointed out and set forth in the appended claims forming part hereof.

In general terms, the faucet of the present invention includes coaxial cylindrical chambers each having at least one inlet port for receiving supply liquid and at least one circumferentially spaced outlet port communicating with said chamber, there being a distributing barrel journaled in each chamber having an annular groove for selectively connecting said inlet and outlet ports, a spring pressed shoe on each barrel for selectively closing off one of said ports, and an exterior axial projection on each barrel for engagement with a single handle for simultaneous operation of both barrels, the shoes being so constructed and arranged that in one position of said handle both syrup and carbonated water are dispensed and in another position, only carbonated water is dispensed.

Referring to the drawing forming part hereof, in which a preferred embodiment of the invention is shown by way of example;

Figure 1 is a vertical sectional view, partly in elevation, of the improved faucet showing two coaxial barrels in shut off position;

Fig. 2 is a fragmentary sectional view taken substantially on line 2—2, Fig. 1, with parts in elevation;

Fig. 3 is a fragmentary vertical sectional view taken substantially on line 3—3, Fig. 1;

Fig. 4 is a fragmentary side elevational view; and

Fig. 5 is a detached isometric view of one of the barrels and its shoe.

Similar numerals refer to similar parts throughout the several views of the drawing.

The improved faucet preferably has a body 10 provided with an inlet neck 11 and an outlet neck 12 at right angles thereto. Supply tubes carrying the liquids to be dispensed from storage reservoirs into the faucet preferably consist of 55 bendable tubes of corrosion-resistant metal and

may include a carbonated water supply tube 13 and a syrup tube 14. These tubes extend through the neck 11 and preferably have their inner ends outwardly flared as indicated at 15 and tightly fitted in sockets in the faucet body by means of nuts 16 surrounding the tubes and screwed into sockets in the faucet body.

The inner end of the carbonated water supply tube 13 communicates with one end of an inlet port 17 the other end of which opens into a cylindrical chamber or bore 18. Similarly, the inner end of the syrup supply tube 14 communicates with one end of an inlet port 19 the other end of which opens into a cylindrical chamber 20. The cylindrical chambers are coaxial horizontally of the faucet body and are separated by a partition wall 21 which may be integral with the faucet body. The cylindrical chamber 18 extends horizontally and is open to one side of the faucet body and the chamber 20 extends horizontally and is open to the opposite side thereof.

Each of the chambers 18 and 20 has an outlet port communicating with the chamber and extending downwardly therefrom to the discharge neck 12. The outlet port communicating with chamber 18 is indicated at 22 and preferably is adapted to carry carbonated water from chamber 18. The outlet port communicating with chamber 20 is indicated at 23 and is adapted to carry syrup from the chamber 20.

Preferably, a discharge spout 24 is screwed into the internally threaded lower end 25 of the discharge neck, and the spout preferably has a knurled rib 26 thereon for facilitating screwing it into the neck portion 25.

A carbonated water discharge tube 27 is located in the spout 24 and is connected with the outlet port 22, as shown. Similarly a syrup discharge tube 28 is located in the spout with its lower end adjacent to the bottom end of the spout and extending alongside of the lower end of tube 27, and with its upper end connected to the syrup outlet port 23.

The tubes 27 and 28 are preferably of corrosion-resistant material and may be secured in the discharge neck 12 in a suitable fashion, as by brazing and preferably have their intermediate portions reversely bent in gradual curves for bringing their lower ends closely adjacent to or touching each other in the lower part of the spout 24.

The means for selectively connecting inlet port 17 with outlet port 22 preferably consists of a distributing barrel 30 journaled in the cylindrical chamber 18, and the means for selectively connecting inlet port 19 with outlet port 23 preferably consists of a similar distributing barrel 31 journaled in the cylindrical chamber 20. Each of the barrels 30 and 31 has a pair of axially spaced ribs 32 which maintain a close journaling fit with the interior of the respective chambers 18 and 20, and these spaced annular ribs form an annular groove or channel extending around the barrel, the annular groove around barrel 30 being indicated at 33, and the annular groove around the barrel 31 being indicated at 34. The port 17 is located between the ribs 32 of barrel 30, and the port 19 is located between the ribs 32 of a barrel 31 so that carbonated water entering through port 17 will flow around annular groove 33 to discharge out of port 22, and similarly, syrup entering through port 19 will flow around groove 34 to discharge out of port 23.

Preferably, the body 10 and the barrels 30 and 31 are made of corrosion-resistant material such

as stainless steel, so that all surfaces contacted by the beverage liquids flowing through the faucet are corrosion-resistant and non-toxic.

Means for closing off one of the ports in chamber 18 preferably consists of a cylindrically curved shoe 35 of fiber or composition material which fits in aligned notches 36 in the ribs 32 of the barrel 30, the shoe conforming in contour with the cylindrical wall of chamber 18 and being pressed outwardly against the same by a pair of springs 37 of corrosion-resistant material seated in sockets 37a in the barrel. In the closed position of the faucet shown in Figs. 1 and 2, the shoe 35 is located directly over the outlet port 22 for shutting off the discharge of carbonated water from chamber 18.

Similarly, the barrel 31 has a cylindrically curved shoe 38 of fiber or composition material fitted in horizontally aligned notches 39 in the ribs 32 of the barrel, and the shoe 38 conforms to the cylindrical wall of chamber 20 and is held against the same by corrosion-resistant springs 40 seated in sockets 41 in the barrel 31. In the closed position of Figs. 1 and 3, the shoe 38 is in position closing off the outlet port 23 to shut off the discharge of syrup from chamber 20, but the shoe 38 has a somewhat greater circumferential length than shoe 35, for a purpose to be described.

Preferably each of the barrels 30 and 31 is provided with an outer neck 42 forming an annular channel around the outer portion of the respective chambers 18 and 20 for receiving suitable sealing gaskets 43 of rubber and the like, and these gaskets may be V-shaped in cross section as shown. Cap plates 44 and 45 are provided to retain the barrels 30 and 31 respectively, in position with their gaskets 43 in sealing position in the chambers 18 and 20 respectively. Preferably the cap plates 44 and 45 are seated on annular shoulders 46 on opposite sides of the faucet body, being clamped thereto by screws 47, and as indicated in Fig. 2, two of the screws may be positioned to form stops for the forward and rearward motions of the faucet handle.

Preferably, each of the barrels 30 and 31 is provided with an axial exterior projection 48 extending through the end caps 44 and 45 and having opposed flat surfaces 49 thereon for receiving bifurcated ends 50 of a handle yoke 51, the ends 50 being secured to the projections 48 by suitable screws 52. At its central portion the handle yoke 51 preferably has a suitable handle lever 53 attached thereto and extending upwardly therefrom.

As shown in Figs. 1 and 2, one of the barrels (in this case barrel 30) has a spring pressed plunger 54 urged against the partition wall 21 between chambers 18 and 20, and the plunger is adapted to frictionally engage in a depression 55 in the partition wall when the handle is in the vertical fully closed position A shown in full lines in Figs. 2 and 3, as an aid to the operator in positioning the handle in fully closed position.

While I have shown a faucet adapted for dispensing water and one kind of syrup, it is obvious that additional kinds of syrup may be dispensed by connecting additional supply lines to the chamber 20 and providing additional annular grooves or channels in the barrel 31 for communicating with said additional ports.

In the operation of the improved faucet, when the handle is in position A, both the carbonated water and the syrup are shut off, because the shoe 35 closes off outlet port 22, and the shoe 38 closes off outlet port 23. When the handle is

moved to the dot-dash position B, the shoe 35 will be moved counterclockwise to the dot-dash position and uncovers the port 22, thus allowing carbonated water to flow through the tube 27 and discharge from the lower end thereof. At the same time the shoe 38 moves counterclockwise to the dot-dash position indicated in Fig. 3 and uncovers the port 23 so that syrup discharges out of the syrup tube 28. When the handle is moved to the dot-dash position C, the shoe 35 is moved clockwise as indicated in Fig. 2 to uncover the port 22 and discharge carbonated water from tube 27 but at the same time the shoe 38 in moving clockwise does not uncover the port 23 because of the greater cylindrical length of shoe 38. Accordingly, in position C of the handle, carbonated water alone is discharged from the spout of the faucet.

It will be apparent from an inspection of the drawings that when the carbonated water enters chamber 18 from port 17, the greater cross sectional area of the annular channel 33 provides for a substantial reduction in velocity and pressure of the carbonated water as it flows into and around the channel 33. Moreover, as the carbonated water passes from the outlet port 22 into the discharge tube 27, the increased diameter of tube 27 will provide a further substantial reduction in the velocity and pressure of the carbonated water, with the result that as the carbonated water is discharged from the bottom end of tube 27, its velocity and pressure has been sufficiently reduced to prevent substantial agitation and turbulency of the carbonated water being discharged into a glass. Accordingly, carbonated water having the desired high content of carbon dioxide gas is dispensed alone or mixed in the glass with the flavoring syrup to provide a mixed drink of maximum palatability, without requiring special diffusing means.

The novel faucet provides a construction which is readily accommodated to the dispensing of several kinds of mixed drinks, and the spring pressed shoes of large area insure a leak-proof seal around the ports over long periods of use.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiment of the improved construction illustrated and described herein is by way of example, and the scope of the present invention is not limited to the exact details of construction.

Having now described the invention, the construction, the operation and use of a preferred embodiment thereof, and the advantageous new and useful results obtained thereby; the new and useful constructions, and reasonable mechanical equivalents thereof obvious to those skilled in the art, are set forth in the appended claims.

I claim:

1. A faucet including a body provided with coaxial cylindrical chambers, a partition wall separating said chambers, said body having a carbonated water inlet port and a circumferentially spaced outlet port each communicating with one of said chambers, said body having at least one syrup inlet port and a circumferentially spaced outlet port communicating with the other chamber, distributing barrels rotatably journaled one in each chamber and each having an exterior annular groove for selectively connecting the in-

let and outlet ports communicating with said chamber, spring pressed cylindrically curved shoes one on each of said barrels conforming to the chamber wall for selectively closing one of said chamber ports, and exterior axial projections one on each barrel engaged with a single handle for simultaneously rotating both barrels.

2. A faucet including a body provided with coaxial cylindrical chambers, said body having a carbonated water inlet port and a circumferentially spaced outlet port each communicating with one of said chambers, said body having at least one syrup inlet port and a circumferentially spaced outlet port communicating with the other chamber, distributing barrels rotatably journaled one in each chamber and each having an exterior annular groove for selectively connecting the inlet and outlet ports communicating with said chamber, spring pressed cylindrically curved shoes one on each of said barrels conforming to the chamber wall for selectively closing one of said chamber ports, and means for simultaneously rotating both barrels.

3. A faucet including a body provided with coaxial cylindrical chambers, a partition wall separating said chambers, said body having a carbonated water inlet port and a circumferentially spaced outlet port each communicating with one of said chambers, said body having at least one syrup inlet port and a circumferentially spaced outlet port communicating with the other chamber, distributing barrels rotatably journaled one in each chamber and each having an exterior annular groove for selectively connecting the inlet and outlet ports communicating with said chamber, a resilient peripheral valve shoe on each of said barrels for selectively closing one of said chamber ports, and exterior axial projections one on each barrel engaged with a single handle for simultaneously rotating both barrels.

4. A faucet including a body provided with coaxial cylindrical chambers, said body having a carbonated water inlet port and a circumferentially spaced outlet port each communicating with one of said chambers, said body having at least one syrup inlet port and a circumferentially spaced outlet port communicating with the other chamber, distributing barrels rotatably journaled one in each chamber and each having an exterior annular groove for selectively connecting the inlet and outlet ports communicating with said chamber, a resilient peripheral valve shoe on each of said barrels for selectively closing one of said chamber ports, and means for simultaneously rotating both barrels.

5. A faucet including a body provided with coaxial cylindrical chambers, a partition wall separating said chambers, said body having a carbonated water inlet port and a circumferentially spaced outlet port each communicating with one of said chambers, said body having at least one syrup inlet port and a circumferentially spaced outlet port communicating with the other chamber, distributing barrels rotatably journaled one in each chamber and each having an exterior annular groove for selectively connecting the inlet and outlet ports communicating with said chamber, the cross sectional area of said groove being substantially greater than that of the inlet port, a spring pressed cylindrically curved shoe on each of said barrels conforming to the chamber wall for selectively closing one of said chamber ports, and exterior axial projections one on each barrel engaged with a single handle for simultaneously rotating both barrels.

6. A faucet including a body provided with coaxial cylindrical chambers, a partition wall separating said chambers, said body having a carbonated water inlet port and a circumferentially spaced outlet port each communicating with one of said chambers, said body having at least one syrup inlet port and a circumferentially spaced outlet port communicating with the other chamber, distributing barrels rotatably journaled one in each chamber and each having an exterior annular groove for selectively connecting the inlet and outlet ports communicating with said chamber, a spring pressed cylindrically curved shoe on each of said barrels conforming to chamber wall for selectively closing one of said chamber ports, an exterior axial projection on each barrel engaged with a single handle for simultaneously rotating both barrels, and a valve shoe on each of said barrels for selectively closing one of said chamber ports, the valve shoe in the syrup chamber being adapted in one position of said handle to close off the discharge of syrup when carbonated water is discharging from the other chamber, and in another position to permit the discharge of syrup simultaneously with the discharge of carbonated water.

7. A faucet including a body provided with coaxial cylindrical chambers, a partition wall separating said chambers, said body having a carbonated water inlet port and a circumferentially spaced outlet port each communicating with one

5 of said chambers, said body having at least one syrup inlet port and a circumferentially spaced outlet port communicating with the other chamber, distributing barrels rotatably journaled one in each chamber and each having an exterior annular groove for selectively connecting the inlet and outlet ports communicating with said chamber, means for simultaneously rotating both barrels, and a peripheral valve shoe on each of 10 said barrels for selectively closing one of said chamber ports, the valve shoe in the syrup chamber being adapted in one position of said handle to close off the discharge of syrup when carbonated water is discharging from the other chamber, and in another position to permit the discharge of syrup simultaneously with the discharge of carbonated water.
